GAIN-CONTROLLING SYSTEM FOR
SEISMOGRAPHS

Edwin J. Shimek, Dallas, Tex., and Goethe M. Groenendyke, Norman, Okla., assignors, by mesne assignments, to Socony-Vacuum Oil Company, Incorporated, New York, N. Y., a corporation of New York

Application June 7, 1944, Serial No. 539,146

10 Claims. (Cl. 177—352)

1

This invention relates to electric seismographs, more particularly to a method and apparatus for controlling the gain in amplification throughout the period of time during which seismic waves created in the earth's surface are being detected and amplified, and has for an object the provision of a system in which there are provided independent adjustments of the amplification characteristics.

A number of methods for controlling the gain in amplification, as derived from thermionic amplifiers, is well known in the art. For example, in Shimek Patent No. 2,317,334, now Reissue Patent No. 22,535, a system is disclosed in which the initial amplification is maintained at a maximum value until signals corresponding with the direct traveling seismic waves have been recorded. The gain is then automatically reduced to a predetermined value in order that reflections of substantial amplitude from relatively shallow interfaces may be recorded on a limited width of recorder strip. The gain in amplification is then caused to increase with time, the purpose being to compensate for the loss in amplitude of the reflections from the deeper strata. While this system represents a substantial advance in the art, the present invention further extends the usefulness of such methods and apparatus for controlling the gain in amplification.

More specifically, there are provided, with a minimum of equipment, a method and means for changing the initial level of amplification without changing the time either for the reduction of amplification, or the time at which the amplification again becomes a maximum. In terms of a seismic survey, this means that the degree of suppression or contraction of the amplification may be selected in any desired manner, and, in particular, to conform with the amplitude of the direct traveling waves and their reflections. The amplitudes of the reflected waves will of course vary according to the character of the subsurface strata giving rise to them. Where maximum gain is required for them it is possible to reduce the initial level of amplification without affecting the time at which amplification again reaches a maximum. Further, in accordance with the invention, the time at which the amplification again becomes a maximum may be changed without affecting the initial level of amplification or the degree of contraction of amplification which may be desired. In terms of a seismic survey, it is emphasized that the expansion of the amplification should conform with the attenuation of the reflected seismic waves. In

asmuch as the attenuation will differ in various localities, the independent adjustments provided are highly advantageous.

Further, in accordance with the invention, there are provided, with a minimum of equipment, a method and means for varying the time rate of change in the gain or expansion of the amplification without changing the overall time from minimum to maximum amplification. This feature is particularly useful where the intermediate reflections in different localities have materially differing amplitudes but where the reflections from the deeper strata require maximum gain in a time interval less than that which would be provided with adjustments which would take care of the intermediate period of expansion of amplification.

For a more detailed description of the invention, and for further objects and advantages thereof, reference should be had to the following detailed description, taken in conjunction with the accompanying drawings in which:

Fig. 1 is a simplified wiring diagram illustrating certain features of the invention together with a fractional and diagrammatic representation of other elements of a seismic surveying system;

Fig. 2 is a graph illustrating three different initial values of the gain-controlling voltage V_s , but in which the time of maximum amplification is the same in each case;

Fig. 3 is a graph illustrating three different rates of rise of the amplification-controlling bias V_s with the initial contraction of amplification, or the initial value of V_s , the same;

Fig. 4 is a simplified wiring diagram illustrating certain additional features of the invention;

Fig. 5 is a graph illustrating one way in which the gain-controlling voltage V_s may be caused to vary;

Fig. 6 is a graph illustrating the overall amplification characteristic with V_s varying, as shown in Fig. 5;

Fig. 7 is a simplified wiring diagram illustrating certain additional features of the invention;

Fig. 8 is a graph illustrating the manner in which V_s may vary at different rates;

Fig. 9 is a graph illustrating the overall amplification characteristics with V_s varying, as shown in Fig. 8;

Fig. 10 is a wiring diagram of the system as a whole and in which there are included the features of Figs. 1, 4 and 7;

Figs. 11 and 12 are graphs illustrating changes in operational characteristics due to movement of

a 3-position switch to each of its positions; and Fig. 13 is a fractional wiring diagram of a preferred system of applying the controlling voltage V_s to a plurality of amplifiers.

In conducting a seismic survey a charge of dynamite, located in a shothole, is detonated. The detonating circuit, as explained in said Shimek Patent No. 2,317,334, includes means for producing a voltage impulse coincidentally with the instant of explosion of the charge. This impulse corresponds with the instant of creation of the seismic waves, and it is recorded on the seismograph as the time break.

In order to show the essentials of the invention in their simplest form, only selected parts of the system have been illustrated in Figs. 1, 4 and 7. These will first be described in detail and then the system as a whole, as shown in Fig. 10, will be explained.

Referring now to Fig. 1, the invention is shown as applied to an amplifier 10 and a geophone 11, which is coupled by transformer 12 to the pentode 13. It is to be understood that additional geophones corresponding with geophone 11 are distributed along a selected area of the earth's surface, and together are known as the "spread." Each of the spread geophones may be provided with an amplifier 10 and each amplifier may include one or more electric valves, only one of which, the pentode 13, is shown in Fig. 1. Preferably two pentode tubes are provided, connected in cascade, each of which is provided with a suppressor grid 14. The amplifier 10 may be of conventional design. As indicated, a coupling capacitor 15 couples the pentode 13 to the next stage of the amplifier, and cathode bias for the control grid of tube 13 is provided as indicated at 16. Seismic signals received or detected by the geophone 11 are applied to the input circuit of the pentode 13 by means of the transformer 12. Amplification of these signals is controlled by suitably varying a negative bias V_s applied to the suppressor grids 14 through a biasing circuit, which includes the conductor 17 and the ground connection G. The output from the amplifier 10 is applied to a recorder 18 which may be of any suitable type, such, for example, as a multi-element recording galvanometer. Each element has a mirror, movable in response to the seismic signals, to produce on a seismogram a trace of oscillographic record of limited width of the signals detected by the geophone 11.

At the instant of creation of the seismic waves a voltage impulse is applied to the input terminals 20 and 21 of a transformer 22. This impulse is of such polarity as to reduce a negative bias, applied by a battery 23, to the control grid of a gas tube 24. The gas tube 24 may be of a type known on the market by the trade name of "Thyratron," and having the characteristic of continued flow of anode current once the control grid loses control. Hence, upon reduction of the negative grid bias by the applied impulse, the Thyratron fires and current flows from a battery 26 through the gas tube 24 and through a resistor 27. The resultant IR drop, or potential difference across the resistor 27, is applied by conductors 32a and 32b to a network comprising capacitors 28 and 29 and resistors 30 and 31.

It is to be observed the upper end of resistor 31 is connected by conductor 32 to ground G and by conductor 32a to a positive tap of battery 26. Thus, before the tube 24 fires, a negative bias V_s is applied to the suppressor grid 14. Its magnitude depends upon the value of the volt-

age across the battery, which is applied to resistors 30 and 31, and by the position of the contactor 33. As the contactor 33 is moved toward conductor 32 the initial negative value of V_s is decreased. The capacitors 28 and 29 are initially charged with the upper plates positive and the lower plates negative, as viewed in Fig. 1. Upon flow of current through the resistor 27, however, the resulting potential difference tends to reverse the polarity of capacitors 28 and 29. They lose their charge at a rate dependent upon the setting of the contactor 34 on the resistor 30. As the contactor 34 is moved upwardly, a greater proportion of the resistor 30 will be included in circuit with the capacitors 28 and 29. This has the effect of increasing the time required for them to lose their initial charge and to reverse in polarity. As the voltage across the capacitors 28 and 29 decreases, the voltage across the resistors 30 and 31 also decreases at a corresponding rate from its initial negative value.

The foregoing operation is graphically illustrated in Figs. 2 and 3. The graphs 33a, 33b and 33c of Fig. 2, plotted with time as abscissae and suppressor grid bias V_s as ordinates, illustrate the operation for differing positions of contactor 33. Thus, with the contactor 33 located with a substantial amount of the resistor 31 included on the ground side thereof, the initial negative bias, as established by the lower section of the battery 26, may be substantial, as indicated at 36. Upon firing of the Thyratron 24 this initial negative bias will decrease, as indicated by the curve 33a, reaching its zero value at time T2. Initially, this high negative bias reduces the gain of the amplifier to a predetermined or preselected low value, such, for example, as would be desired for the reception of shallow reflections or direct traveling seismic waves. During the time interval from zero to T2 the negative suppressor grid bias V_s decreases to zero and the amplification is correspondingly increased. The amplification reaches a maximum as the suppressor grid bias approaches zero. The amplification is not increased as the suppressor grid bias is made positive with respect to the cathode. The relation between amplification and suppressor grid bias is well understood in the art, and reference may be had to Minton et al. Patent No. 2,301,739, for illustrative graphs with respect thereto.

An important feature of the present invention is that adjustment of the contactor 33 is effective in changing the initial negative bias without changing the time, such as the time T2, at which the amplification reaches a maximum. Thus, if the contactor 33 is moved upwardly by a predetermined amount, as viewed in Fig. 1, the initial negative bias will be reduced to a value, as indicated at 37. Upon firing of the Thyratron 24, however, the negative bias will decrease, as indicated by the curve 33b, with the time of maximum amplification attained at T2, as before. Similarly, if the contactor 33 is moved to include still less resistance, the initial value of the negative bias will be as indicated at 38 and again maximum amplification will be attained during the same finite time interval, as indicated at T2. It may be observed that the various curves 33a to 33c intersect and cross each other at the point T2, but this fact is immaterial inasmuch as a positive bias on the suppressor grid does not affect the amplification characteristics. This fact makes possible the use of an applied potential opposite in polarity to the initial charge on capacitors 28 and 29. This feature is in con-

trast with prior suggestions where a capacitor is discharged through a resistor.

The reason the adjustment of the contactor 33, with respect to the resistor 31, does not affect the time at which the amplification will be a maximum is that the total resistance of resistors 30 and 31 remains unchanged insofar as the applied potential differences are concerned. In other words, the parameters of the time-delay circuit, including the capacitors 28 and 29, are not 10 changed by movement of the contactor 33.

Similarly, adjustment of the contactor 34, with respect to the resistor 30, does not change the parameters of the circuit which includes the conductor 17 and ground connection G. However, as shown in Fig. 3, the adjustment of the contactor 34 does change the resistance in the charging circuit of the capacitors 28 and 29. For comparative purposes the curve 33b of Fig. 2 is reproduced in Fig. 3 as curve 34b. It represents the conditions with the contactors in the positions shown in Fig. 1. If the contactor 34 be moved downwardly to decrease the amount of resistance in series with the capacitors 28 and 29, the maximum negative bias indicated at 37 remains unchanged. However, upon the firing of the Thyratron 24 the capacitors 28 and 29 will discharge more rapidly, and after reversal of their polarity, will be more rapidly charged, as indicated by the curve 34a. If the contactor 34 be moved upwardly to include more resistance in the time-controlling circuit, the rise in voltage is at a lower rate, as shown by the curve 34c. Thus, adjustment of the contactor 34 changes the rate at which the suppressor grid bias V_s decreases from a predetermined negative value to zero, and thence to a positive value. The result, of course, is a change in the time interval required for V_s to be reduced to zero. The times at which maximum amplification occurs for the three curves 34a, 34b and 34c are indicated at T1, T2 and T3.

It will now be seen that there is provided independent control of the extent of the initial contraction of the amplification and the time rate at which the amplification increases or expands. It is, therefore, possible to preset the amplifier strictly in accordance with the amplitude characteristics of the seismic waves detected by the spread geophones, whether they be direct traveling or reflected waves. Either the extent of the initial contraction, or the time from the instant of contraction to maximum amplification may be adjusted independently of each other, or both may be adjusted between relatively wide limits to meet widely varying field requirements. In this manner, improved records are attained in less time, records which may be more readily interpreted and which, because of relatively exact compensation for changes of amplitude, may be read more accurately and with relatively greater ease than has heretofore been possible.

Referring now to Fig. 4, provision is also made for initial operation, with the amplifier set for maximum gain. This is desirable in most seismic surveying systems in order that the first breaks which appear at the spread geophones may be recorded with maximum accuracy. The first breaks correspond with the instant of arrival at the respective geophones of the direct traveling seismic waves. These waves travel directly from the shotpoint through the upper and weathered layer of the earth's surface. By ascertaining the travel time from the shotpoint to the respective geophones, calculations may be made to ascertain the velocity of the waves through the weath-

ered layer. Inasmuch as the instant of arrival of these waves is the principal thing of interest, the recordation, with maximum gain by the amplifier, produces a sharper break than would be the case if the amplification were substantially reduced. That is to say, the application to the galvanometer of a signal of substantial magnitude produces an abrupt movement of the galvanometer coil, and the galvanometer mirror in turn causes the light beam on the film or seismogram to move from its resting position abruptly in one direction or the other. Even though the light beam is moved beyond the confines of the relatively narrow recorder strip, nevertheless the sharp "break," or movement of the beam from its resting position, provides clear and accurate indication of the instant of arrival of the direct traveling waves.

As shown in Fig. 4, it will be observed that the lower end of the resistor 31 is connected by conductor 40 to a normally open contact 41 of a high speed relay, diagrammatically illustrated at 42. Until the relay 42 is operated to complete a circuit through the normally open contact 41, it is obvious that the suppressor grid bias V_s is zero. It is zero because resistor 31 is not connected in the circuit. The gain, or the amplification, of the amplifier 10 (shown only in Fig. 1) is a maximum. The relay 42 is also provided with a normally closed contact 43 which serves to connect a resistor 44 in series-circuit relation with the resistor 30. This connection may be traced from the resistor 30 through a manually operable switch 45, the arm of the relay 42, the normally closed contact 43, and through the resistor 44 to the conductor 32. The resistors 31 and 44 are identical. Hence, so far as the circuit is concerned, in terms of the operating characteristics described in connection with Figs. 1-3, the operation is identical with either the resistor 31 or the resistor 44 in series with the resistor 30.

It will be understood that only a relatively short time interval is required for the direct traveling wave to reach the spread geophones. After expiration of this time interval, the relay 42 is energized to open the circuit at the contact 43 and to close the circuit through the contact 41. The resistor 31 is thereby substituted in the circuit in place of the resistor 44. Hence, the voltage which appeared across the resistor 44 at once appears across the resistor 31, and is applied through the conductor 17 and the ground connection G to the suppressor grids substantially instantaneously to contract or to reduce the amplification or gain in the amplifier. The resistor 44 is, in effect, a dummy resistor which permits the removal of resistor 31 without affecting the circuit constants of the controlling circuits. As above explained, at the instant of detonation of the charge, the Thyratron 24 fires and a voltage, or potential difference, immediately appears across the resistor 27. A part of that voltage is applied to a circuit, which may be traced from a part of the resistor 27 by the switch 46, adjustable contactor 47 of a resistor 48, a capacitor 49, and by conductor 50 to the other side of resistor 27. The resistor 48 controls the charging time of the capacitor 49, which, it will be observed, is connected in circuit with a bias battery 51 and a resistor 52 in the grid circuit of a Thyratron 53. The bias battery 51 normally negatively biases the Thyratron 53 to prevent flow of anode current. However, as the voltage rises across the condenser 49 it is of

such polarity as to reduce the negative bias from battery 51. At a predetermined time interval the bias is reduced to a point where the Thyratron 53 fires. Current then flows from the positive end of battery 26 by way of conductor 54, the operating winding of the relay 42, conductor 55, through the Thyratron 53, and by conductor 50 to the negative side of battery 26. The high speed relay 42 is, in this manner, operated to substitute resistor 31 in the circuit in place of resistor 44. By suitable adjustment of the contactor 47, the time of operation of the Thyratron 53 and of the relay 42 may be adjusted to suit the requirements of the particular seismic survey being conducted. Any particular setting will depend upon the spacing of the spread geophones from the shothole, and upon the velocity characteristics of the weathered layer in the region being explored.

Graphically, the foregoing operations are illustrated by the graph of Fig. 5 of the suppressor grid bias, and the graph of Fig. 6 of the corresponding changes in the over-all amplification of the amplifier. At the instant of detonation, the suppressor grid voltage V_s is zero, as indicated at T_0 , which corresponds with maximum amplification by the amplifier. After a time interval, adequate for the direct traveling waves to reach the spread geophones, the Thyratron 53 fires, as at the time T_4 , and the high speed relay 42 operates to connect the resistor 31 in the circuit. The gain-controlling bias is then immediately applied to the amplifier, as indicated at 57. The effect is immediately to reduce or contract the amplification to a predetermined value, as indicated at 58, Fig. 6. Thereafter, the operation is as described above, and the amplification is gradually increased, as indicated by the full line curve 59, which corresponds with a decreasing negative bias, as indicated by the full line curve 60 of Fig. 5. By adjusting the position of the contactor 47 it will be observed that the instant at which the contraction occurs may be changed. If it is later than as shown in Fig. 6, then the degree of contraction will be less. In other words, at the time T_4 the contraction indicated at 58 is less than at the time T_0 . If greater contraction is desired at the time T_4 it will be recalled that the contactor 33 may be moved in the correct direction (downwardly in Figs. 1 and 4), negatively to increase the gain-controlling voltage V_s . It will also be remembered this adjustment does not affect the other operating characteristics, particularly the time at which maximum amplification is attained. Neither does the value of the time assigned to T_4 alter the magnitude of V_s which would have existed at time T_4 had the "first break" feature not been operative.

In certain areas in which geophysical surveys are made, the geological structure may comprise relatively shallow reflecting interfaces followed by interfaces at substantial depths, such as five thousand feet or more. In such cases, it is desirable to establish a maximum amplification at a time interval materially shorter than would be provided by a characteristic curve such as 34c in Fig. 3, or such as the curve 59 of Fig. 6. In other words, the objective is to correlate the amplification with the amplitude of the reflections received. As soon as the need for contraction has passed, it is desirable immediately to provide maximum amplification for the following reflections of lesser amplitude.

For simplicity, provisions for the foregoing are

shown in Fig. 7, as applied to the simplified circuit forming a part of Fig. 1. These provisions comprise a high speed relay, diagrammatically shown at 63, with a normally closed contact 64 inserted in series with the capacitor 28. As long as the contact 64 remains closed, the operation is identical, as described above in connection with Figs. 1 and 4. Specifically, referring to Fig. 8, the gain controlling voltage V_s decreases from a maximum negative value 66 in accordance with the characteristic curve 65. At a time T_6 it is desired to have the amplification at a maximum. Therefore, at a time T_5 the bias is rapidly decreased along the broken line curve 66 reaching zero at T_6 , this value corresponding with maximum amplification. In terms of amplification, the expansion is from a predetermined low value, as indicated by curve 62 in Fig. 9, to a higher value, as indicated at the time T_5 . Thereafter the gain rapidly rises, as shown by the broken line curve 67, reaching the maximum at time T_6 . If the capacitor 28 had been omitted throughout the aforesaid cycle of operations, the characteristic curve would then be as shown by the curve 68 of Fig. 8, with a corresponding amplification as shown by the curve 69, Fig. 9. Thus the effect of opening the contact 64 and removing the capacitor 28 from the circuit changes the operation from one characteristic curve to the other characteristic curve. The same result may be achieved by decreasing the resistance in circuit with capacitors 28 and 29, although this arrangement has not been illustrated. For such a modification, the contact 64 of relay 63 would be arranged to change the effective position of the tap 34 to change the resistance, in circuit with capacitors 28 and 29, from an initial high value to a predetermined low value, the effect of which would be to transfer the operation from curve 34c, taken by way of example, to curve 34b, of Fig. 3.

The operating coil of the relay 63 may be energized under the control of a gas tube, or Thyratron 70. In this case, a negative bias, derived from resistor 31, is utilized normally to bias the control grid of the Thyratron 70 to prevent flow of anode current. To control the time at which anode current flows, it is desirable to include in the input circuit, including the control grid, a bias battery 71 connected to oppose the negative voltage from resistor 31. It will be observed this circuit also includes a variable resistor 72. The circuit constants are selected so that as the negative voltage across resistor 31 decreases to a value at time T_5 , Fig. 8, the Thyratron 70 fires. Current then flows from the battery 26 by way of the operating coil of relay 63, the Thyratron 70, and thence by conductors 32 and 32a to the negative side of battery 26. The relay 63 is preferably a high speed relay which operates immediately to open the contact 64, thus removing the capacitor 28 from the circuit and causing the above described rapid decrease in the gain controlling voltage V_s from its negative value. This produces the rapid rise in the amplification, which has also been described.

With the above understanding of the simplified forms of the invention, it will be understood that many modifications and permutations may be made without departing from the spirit of the invention. Tubes of suitable characteristics may be substituted for the gas tubes, or Thyratrons, and in lieu of the utilization of a change of the bias on the suppressor grids, the amplification characteristics of the amplifier may be altered in other ways understood by those skilled in the art.

The manner in which the several features of the invention thus far described are combined into a single unitary system or master controller, will now be explained in connection with Fig. 10. The system of Fig. 10 combines the several features illustrated in Figs. 1, 4 and 7. It will be observed that in addition to capacitors 28 and 29 there are provided in parallel therewith capacitors 73-78. These capacitors are connected in parallel by the upper deck 80 of a gang switch, which is also provided with a lower deck 81 and additional decks comprising contactor 82 associated with resistor 27, and contactor 83 associated with resistor 72. As shown, the capacitors 73-78 are connected in parallel with capacitors 28 and 29. The resistor 27 is provided with three taps with which cooperate a contactor 85. This contactor 85 is mechanically interlocked with contactors 86 and 87 respectively associated with capacitors 28 and 29, and with contactor 88 associated with resistor 91. The contactor 47 is shown in full line as in an "off" position, and by broken lines it is shown in its first position in which the input circuit for the gas tube 53 is completed. In this manner, the contactor 47 performs the function of the switch 46 of Fig. 4.

The contactors 85-88 are all shown in their No. 1 positions. It will be observed the capacitor 28 is not connected in circuit with the contact 64 of the relay 63. Instead, the contact 64 is connected to the deck 81 of the gang switch. In the first position from "off" position of the gang switch 80-83 the decks 80 and 81 move to the right, and in doing so the capacitor 73 is inserted in a series-circuit which includes contact 64 of the relay 63.

With all parts in the illustrated positions the Thyatron 53 will not fire since contact 47 is in its first, the "off" position. Hence, relay 42 cannot be closed. Therefore amplification is at a maximum since resistor 31 is excluded from the circuit and V_s is zero. The manual switch 94 may be moved to its vertical position to connect resistor 31 in the circuit in place of resistor 44 and independently of relay 42. The system will then function to control the expansion under the control of contactors 33 and 34 and their associated circuits, but the relay 42 will be ineffective.

There are several independent controls. The adjustment of contactor 33 determines the magnitude of the initial negative bias developed between the contactor 33 and ground and applied to the suppressor grids. The adjustment of contactor 34 predetermines the time during which expansion of the amplification takes place. Therefore, contactor 34 may be calibrated in seconds; that is, when it is moved from .6 to 4.0, the time from the time of the shot instant until maximum amplification will be that selected, as six-tenths of a second, four seconds, or as shown, 1.4 seconds.

Advantage is taken of the use of the negative bias from resistors 31 and 44 to prevent the firing of the Thyatron 70. Since the time-determining contactor 34 varies the time of maximum amplification, it will be seen that the time of the firing of Thyatron 70 will vary therewith. If the time is long, the firing of tube 70 will occur at a proportionately later time. Therefore, by providing the resistor 72 with a series of taps arranged for cooperation with the deck 83 of the gang switch 80-83, the positions of the gang switch may be calibrated in terms of the per cent of the time, selected by the positions of the con-

tactor 34. The inclusion of a potentiometer circuit in the grid circuit of Thyatron 70 enables the potential of the grid of tube 70 to be varied in order to produce firing of the Thyatron 70 at the desired percentage of the time determined by the position of the contactor 34. For example, with the gang switch 80-83 in its first position, the Thyatron fires after expiration of (.4) forty per cent of the time selected by contactor 34. This dependent or proportional relation makes possible the calibration of the gang switch in terms of per cent of the time selected by the contactor 34.

With the gang switch 80-83 in its final (.9) position, the Thyatron 70 fires after expiration of 90% of the time selected by the contactor 34. Thus, with the gang switch in its first position, the relay 63 operates in $.4 \times 1.4 = .56$ seconds after Thyatron 24, while in the last position the relay operates on $.9 \times 1.4 = 1.26$ seconds after the firing of the Thyatron 24.

Even with the relatively wide flexibility thus described, the total time from the shot instant, or the firing of Thyatron 24, to the time of maximum amplification remains substantially unchanged. This is accomplished by changing the circuit constants and applied voltage by means of the decks 80, 81, and 82. Briefly, as the gang switch is moved to increase the per cent time (from .4 to .9) the decks 80 and 81 connect the capacitor 73 in series with the contactor 64. In the next position the capacitors 73 and 74 are included in that circuit, and in the final position all of the capacitors 73-78 are in circuit therewith. In consequence, more capacity is removed from the time-delay circuit by relay 63 as the per cent time is increased. The removal, or decrease, of the capacitance decreases the time required for V_s to reach zero. Thus, the relative values are selected so that the overall time remains substantially constant.

There is also an independent adjustment for the contactor 47 along resistor 48, which controls the initial time during which the amplification is maintained at a maximum for recordation of the first breaks due to the direct traveling seismic waves. The position of contactor 47 along resistor 48 may be calibrated in fractions of a second, as from one-tenth to six-tenths of a second.

A further control feature of the invention is provided by the mechanically interlocked 3-position switches 85-88. When the contactor 85 is moved from its first to its second position (with deck 82 in any position from .4 to .9) a smaller portion of the resistor 27 is connected across the network. The reduction in this resistance reduces the applied voltage and results in a greater reduction in amplification during the period of time determined by contactors 80, 81, 82, and 83. A further reduction in amplification occurs upon movement of contactor 85 to its No. 3 position. The increase in V_s also appears in the input, or control, circuit of the Thyatron 70. However, the contactor 88 adjusts the potential drop across the stepped resistor 72 in a direction such that the Thyatron is fired at the proper time corresponding to the position of contactors 83 and 34.

The contactors 86 and 87 serve first to include the capacitor 28 and finally the capacitor 29 in circuit with relay contact 64, in order to keep the overall expansion time constant at the value indicated by contactor 34.

The foregoing is illustrated in the graphs of

Figs. 11 and 12. With the 3-position switch in its No. 1 position, it will be observed that the negative biasing voltage V_s has an initial value indicated at $-V$. This voltage rises in accordance with the curve 85a until the time indicated at T7. At this instant the relay 63 operates to remove from the circuit those capacitors which have been connected in series with the contact 64. Thereafter, the biasing voltage V_s rises at an increased rate, reaching substantially zero at the time T8. By reducing the potential difference, as by moving the 3-position switch 85-88 to its No. 2 position, the discharge of the capacitors occurs at a lower rate, as indicated by the curve 85b. However, in the second, or No. 2, position the capacitor 28 is included in circuit with the contact 64 of relay 63. Hence, upon operation of relay 63 at the time T7 this capacitor is also excluded from the circuit. Its value is such that the negative bias decreases at a still greater rate and reaches zero at the time T8. In this manner the rate of rise of the negative bias may be selected, or predetermined, in accordance with the conditions imposed by the area over which the seismic survey is being made. Even though the rate of change over the initial period may be adjusted, the maximum amplification is attained during the same time interval in both cases. This is clearly shown by the corresponding curves 85c and 85d, where maximum gain of amplification is attained at time T8. In the third position the rate of rise of the negative bias is at a much lower rate, as indicated by the curve 85e. However, in this position of the switch both of capacitors 28 and 29 are now included in circuit with the contact 64 of relay 63. Hence, when this relay operates at the time T7, both capacitors are removed from the circuit and the rate of rise of the negative bias in a positive direction is at a very high rate, and adequate to insure that it reaches zero at the time T8, as before. Similarly, the corresponding gain curve 85f shows the gain gradually increasing to the time T7, with a very rapid expansion of amplification until it reaches maximum at the time T8, as before.

It will now be seen that the curves shown in Figs. 2, 3, 5, 6, 11 and 12 are illustrative of but a few of the large family of characteristic curves made possible by the relatively simple adjustments which have been described. With many differing basic characteristic curves, the many additional adjustments provide for nearly every desired operation. The time for the initial contraction may take place anywhere from zero (the time of the shot instant or the time of firing of tube 24) to six-tenths of a second, and, with all of the variable predetermined conditions of operation during the expansion, the overall expansion time may be the same or made constant regardless of wide changes in the other characteristics.

Without repeating the previous detailed description, it may be observed that movement of the gang switch 80-83 to the first or .4 position, through contactor 82, removes the lowermost section of resistor 27 from the network connected between contactor 86 and conductor 32a. At the same time, the first section of resistor 72 is inserted in the grid circuit of Thyatron 70. This compensates for the reduced applied voltage and the reduced rate of voltage change across resistors 31 or 44, and, as already explained, the capacitor 73 is placed under the control of the relay 63 in order that the total time shall be

constant, with relay 63 operating after expiration of 40% of the time selected by contactor 34.

For additional flexibility, the refinements illustrated in the fractional diagram of Fig. 13 may be utilized. The resistor 30 is shown calibrated for time intervals from 0.6 of a second to 5 seconds. As in Fig. 10, the contactor 34 is shown at a position corresponding with the time of 1.4 seconds. The manual switch 94 of Fig. 10 is replaced by a 3-position switch having a contactor 97, the first position of which is an "off" position, while the second and third positions correspond to the two positions shown for the switch 94 of Fig. 10. In Fig. 13 the resistors 31 and 44 are provided with contactors 98 and 99 mechanically connected together for simultaneous movement. Thus, by changing the position of contactors 98 and 99 with respect to resistors 31 and 44, the value of the gain controlling voltage V_s is increased or decreased, depending upon the direction of the adjustment. This gain control voltage is applied to a resistor 100 which serves as a multiple potentiometer arrangement for each amplifier. As is well understood in the art, each geophone is preferably provided with its own amplifier, and the gain control therefor is preferably adjusted separately from the other amplifiers. For example, a number of amplifiers are symbolically designated at 101, 102, 103, 104 and 105. By moving the contactor 106 downwardly to a position corresponding with the one marked "4," a predetermined negative bias will be applied to the suppressor grids of the amplifier 101. If the geophone corresponding with the amplifier 102 receives early reflections whose amplitudes are somewhat different than those received by the geophone associated with the amplifier 101, then the contactor 107 may be moved to a different position, such as position 3 or position 5. Similarly, the contactors 108, 109 and 110 may be set for the desired magnitude of the initial suppressor voltage. In this way the amplifier for each geophone of the spread may be separately adjusted without affecting the operation of any of the other amplifiers or of the amplifiers taken as a group.

It is to be understood that each of the taps 1-13 are connected in the manner illustrated for the taps 1-3. Further, it is to be understood that many more geophones and amplifiers than the five, 101-105, are generally used. For simplicity only a few have been indicated, but as many as may be desired may be used by simply increasing the number of contactors corresponding with 106-110 and by extending the taps for cooperation therewith.

It will also be seen that the magnitude of the gain-controlling bias may be adjusted simultaneously for all the amplifiers by means of the contactors 98 and 99. With these various provisions adjustments can be made to take care of widely differing terrain, which, in terms of a seismic survey, means that the data may be distinctively recorded and interpreted with greater accuracy. In many cases these adjustments make possible the securement of satisfactory data, which might otherwise be unattainable for a locality.

While the foregoing description is largely in terms of the control of the gain or amplification of the geophone amplifier, the invention as applied to the seismic recording system may be considered in terms of the sensitivity thereof. This recording system, including the geophone, the amplifier and the recording galvanometer ele-

ment which produces the seismogram, is provided with an adjustable sensitivity which is varied in accordance with the intensity of the seismic signals to be recorded. In effect, the gain-controlling network, Fig. 10, between the conductors 32a and 32b comprises the section of resistor 39 in series with the several capacitors, which are connected in parallel with each other. The resistors 30 and 31 are connected directly across the network. They could, of course, be replaced by a single resistor. In other words, they may be considered as a single resistor insofar as they provide a constant resistance across the applied sources of potential difference. Considering them in this way, they may be considered as forming a potentiometer. The lower part of this potentiometer, or resistor 30-31, is utilized to control the decay of the initial negative bias or the charge applied to the capacitors.

It is to be further observed that the application of the second potential difference of opposite polarity forces, or hastens, the decay, or discharge, of the capacitors. Inasmuch as this second applied potential difference may be controlled by contactor 85, the permissible variation is over a range materially and substantially greater than if such forced discharge were not utilized. Moreover, as will be observed from the various curves, Figs. 2, 3, 5, 6, 8, 9, 11 and 12, the contraction and expansion of the amplification, as well as the rate of rise of the biasing voltage V_s , is relatively uniform. While not linear, the straighter portions of the exponential rates of decay are, to a large extent, utilized, though the amplification may be expanded, as already explained, so that the lower rate of decay of the negative biasing voltage V_s may be utilized.

While a preferred embodiment of the invention has been described, it will be understood that modifications may be made without departing from the spirit and scope of the invention as set forth in the appended claims.

What is claimed is:

1. In a seismograph system having a detector of seismic waves transmitted through the earth, an electrical recorder of said waves and a thermionic amplifier interconnecting said detector and said recorder, said amplifier having means responsive to a negative bias for controlling the contraction and expansion of the amplification thereof, the combination of a resistor, a source of potential for producing a potential difference across said resistor, means for applying this potential difference to said amplifier as said negative bias, capacitors, a charging circuit for said capacitors including said source of potential and a part of said resistor, means for applying to said resistor and to said capacitors a potential difference of polarity opposite to that of said source to produce a forced decay of said negative bias to zero and thence to a positive value, means for producing said decay at different selected time rates between a low limit of high negative bias and a high limit of zero bias without changing the time interval between said low limit and said high limit, and means for changing the initial high negative value of said bias without changing the time at which said bias is reduced to zero.

2. In a system having an amplifier and a recorder for recording signals applied to said amplifier, said amplifier having means responsive to a negative bias for controlling the contraction and expansion of the amplification thereof, the combination of means including a timing circuit having a plurality of parallel-connected capaci-

tors therein for applying to said amplifier a relatively high negative bias to produce substantial contraction of the amplification, means including said capacitors for decreasing said negative bias at a predetermined time rate to produce during a predetermined time interval an expansion of the amplification of said amplifier from a predetermined low limit to a predetermined high limit, means operable at any one of a plurality of selected times within said time interval for differently increasing the time rate of expansion of said amplification in manner such that the length of said time interval is constant regardless of which of said times is selected, said last-named means including a switch for removing from said circuit an increasingly larger number of said capacitors as said selected time approaches the end of said time interval.

3. In a process of seismic prospecting in which the amplitude of seismic signals received at a recording system decreases as a function of time and in which an amplifier is provided to increase the amplitude of said signals, the combination of means for controlling the gain of said amplifiers at a predetermined time rate comprising a resistor, means for applying a predetermined voltage across said resistor, means including a capacitor for controlling the rate of rise of voltage across said resistor, said capacitor being connected in series with at least a part of said resistor and in shunt with the remaining portion of said resistor, means for changing the amount of said resistor in circuit with said capacitor thereby to change the rate of rise of voltage across said resistor without changing the initial value thereof, and adjustable means for deriving from said resistor a gain-controlling voltage, the adjustment of said means with respect to said resistor predetermined such initial gain-controlling voltage.

4. In a system of seismic prospecting in which the amplitude of seismic signals received at a recording system decreases as a function of time and in which an amplifier is provided to increase the amplitude of the received signals, the combination of means for controlling the gain of said amplifier at a predetermined time rate comprising a resistor, means for producing a predetermined voltage across said resistor, a second resistor identical with said first resistor, means for producing a voltage rise across said first resistor from a predetermined negative value to a lower negative value and thence to a positive value, means operable at a predetermined time for substituting said second resistor for said first resistor, means including said second resistor for applying a gain-controlling voltage to said amplifier to suppress the gain thereof and thereafter to increase the gain thereof.

5. In a system of seismic prospecting in which the amplitude of seismic signals received at a recording system decreases as a function of time and in which an amplifier is provided to increase the amplitude of the received signals, the combination of means for controlling the gain of said amplifier at a predetermined time rate comprising a resistor, capacitive means included in circuit with said resistor, means for deriving a gain-controlling biasing potential from a part of said resistor, means for initially establishing a predetermined gain-suppressing biasing potential across said resistor, means for changing said biasing potential at a predetermined time rate and in a direction to increase the gain of said amplifier, and means operative at a predeter-

mined time interval, after said biasing potential has risen a predetermined amount, for substantially decreasing the capacity of said capacitive means, thereby abruptly to change said biasing potential in a direction rapidly to increase the amplification of said amplifier.

6. In a seismograph system having a detector of seismic waves transmitted through the earth, an electrical recorder of said waves, and a thermionic amplifier interconnecting said detector and said recorder, said amplifier having means responsive to a negative bias for controlling the contraction and expansion of the amplification thereof, the combination of a network comprising a circuit including a plurality of capacitors in parallel with each other and in series with a resistor, a second resistor in series with said first resistor and connected across said network independently of the circuit including said capacitors, means for applying to said amplifier a bias from said second resistor, a source of supply for applying a potential of one polarity to said network negatively to charge said capacitors and to produce across said second resistor a negative bias of magnitude adequate greatly to reduce the amplification of said amplifier, means for applying to said network a potential of opposite polarity for reducing said negative charge of said capacitors, thereby to decrease said negative bias at a predetermined time rate, means operable a time interval after application of said second potential to said network for reducing the number of capacitors connected across said network to change the time rate of decrease of said negative bias, means for varying said time interval, and switching means operable concurrently with said last-named means for increasing the number of capacitors excluded from said network as said time interval is increased.

7. In a system having an amplifier and a recorder for recording signals applied to said amplifier, said amplifier having means responsive to a negative bias for controlling the contraction and expansion of the amplification thereof, the combination of means including a timing circuit having capacitive means therein for applying to said amplifier a relatively high negative bias to produce substantial contraction of the amplification, means including said capacitive means for decreasing said negative bias at a predetermined time rate to produce during a predetermined time interval an expansion of the amplification of said amplifier from a predetermined low limit to a predetermined high limit, means operable at any one of a plurality of selected times within said time interval for differently increasing the time rate of expansion of said amplification in manner such that the length of said time interval is constant regardless of which of said times is selected, said last-named means including means for removing from the circuit an increasingly greater proportion of the capacitance of said capacitive means as said selected time approaches the end of said time interval.

8. In a system having an amplifier and a recorder for recording signals applied to said amplifier, said amplifier having means responsive to a negative bias for controlling the contraction and expansion of the amplification thereof, the combination of means including a timing circuit having a plurality of parallel-connected capacitors therein for applying to said amplifier a relatively high negative bias to produce substantial contraction of the amplification, means including said capacitors for decreasing said negative bias

75

at a predetermined time rate to produce during a predetermined time interval an expansion of the amplification of said amplifier from a predetermined low limit to a predetermined high limit, means for varying within relatively wide limits said time rate of expansion of said amplification, means operable at a predetermined time interval after expansion of said amplification at a selected rate for increasing the time rate of further expansion of said amplification to a degree such that the length of the time interval between said low limit and said high limit is constant regardless of the rate selected for said initial expansion of said amplification, said last-named means including means for removing from said circuit an increasingly larger number of said capacitors as said selected time rate of initial expansion is made less.

9. In a system having an amplifier and a recorder for recording signals applied to said amplifier, said amplifier having means responsive to a negative bias for controlling the contraction and expansion of the amplification thereof, the combination of means including a timing circuit having a plurality of parallel-connected capacitors therein for applying to said amplifier a relatively high negative bias to produce substantial contraction of said amplification, means including a selector switch for varying the number of said capacitors in said timing circuit thereby to change the time rate of decay of said negative bias to produce an initial expansion of said amplification at a selected time rate, means operable after a predetermined time interval for increasing the time rate of expansion of said amplification to a degree such that the length of the time interval from the beginning of said expansion from said low limit to a predetermined high limit is constant regardless of the selected time rate of said initial expansion, said last-named means including a switch for removing from said timing circuit a predetermined number of said capacitors, an electric valve for controlling operation of said switch, means for applying said negative bias to said valve initially to render it non-conductive and means operable concurrently with said selector switch for so changing the bias on said valve as to render said valve conductive at the end of a predetermined time interval regardless of the selected rate of decay and of the magnitude of said negative bias.

10. In a seismograph system having a detector of seismic waves transmitted through the earth, an electrical recorder of said waves and a thermionic amplifier interconnecting said detector and said recorder, said amplifier having means responsive to a negative bias for controlling the contraction and expansion of the amplification thereof, the combination of a resistor, a source of potential for producing a potential difference across said resistor, means for applying this potential difference to said amplifier as said negative bias, capacitive means, a charging circuit for said capacitive means including said source of potential and a part of said resistor, means for applying to said resistor and to said capacitive means a potential difference of polarity opposite to that of said source to produce a forced decay of said negative bias to zero and thence to a positive value, means for producing said decay at different selected time rates between a low limit of high negative bias and a high limit of zero bias without changing the time interval between said low limit and said high limit, and means for changing the initial high negative value

17

of said bias without changing the time at which said bias is reduced to zero.
